DESCRIPTION

FIG. 1 is a front view of a first image in a sequence for a display screen with a menu wheel icon for a user interface;

FIG. 2 is a front view of a second image thereof;

FIG. 3 is a front view of a third image thereof; and,

FIG. 4 is a front view of a fourth image thereof.

The appearance of the animated image sequentially transitions between the images shown in FIGS. 1 to 4.

The process or period in which one image transitions to another image forms no part of the claimed design.

The broken line showing of the portion of the display screen in all views is for the purpose of illustrating unclaimed portions of the display screen with a menu wheel icon for a user interface and forms no part of the claimed design.
